CLAIM

The ornamental design for a notebook computer as shown and described.

DESCRIPTION

FIG. 1 is a rear top perspective view of a notebook computer showing our new design;

FIG. 2 is a rear bottom perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof;

FIG. 8 is a bottom view thereof;

FIG. 9 is a cross-sectional view taken along line 9-9 in FIG. 3;

FIG. 10 is an enlarged view of the portion, labeled '10' in FIG. 1;

FIG. 11 is an enlarged view of the portion, labeled '11' in FIG. 2;

FIG. 12 is an enlarged view of the portion, labeled '12' in FIG. 3; and,

FIG. 13 is an enlarged view of the portion, labeled '13' in FIG. 5.

The evenly-dashed broken lines illustrate portions of the notebook computer that form no part of the claimed design. Unshaded surfaces form no part of the claimed design. The dot-dash broken lines in FIG. 3 illustrate the cross-section line and form no part of the claimed design. The dot-dot-dash broken lines illustrate the extents of the enlarged views and form no part of the claimed design.
